UNITED STATES PATENT OFFICE

ROBERT E. LYFORD, OF CHICAGO, ILLINOIS, ASSIGNOR TO INTERNATIONAL HARVESTER COMPANY, A CORPORATION OF NEW JERSEY

SUPERCHARGER AIR CLEANER

Application filed February 7, 1930. Serial No. 426,574.

This invention relates to devices for circulating, cleaning, and compressing a gas. More particularly, it relates to a super-charger air cleaner for internal combustion engines.

The principal object of the invention is to move, clean, and compress one stream of gas by direct contact with another stream of gas at a comparatively high velocity without any substantial mixing of the two gases.

Another object is to carry the material removed from the gas being cleaned away in the high velocity gas stream.

A particular object is to apply the invention to internal combustion engines and to utilize the exhaust gas from the engine for cleaning and super-charging the air to be used for combustion.

Other objects will be apparent from the detailed description to follow.

The objects of the invention are accomplished by utilizing the property of a gas stream issuing through an opening from a chamber containing the gas under pressure to expand uniformly and to follow a predetermined path. The stream is passed through spaced, aligned openings of a size to accommodate the stream without interfering with the directional flow. A stream of gas to be cleaned is drawn into contact with the high velocity stream by an injector action and by surface friction with the high velocity stream.

Devices embodying the invention are so designed that the stream of gas to be cleaned will be delivered against the high velocity stream at an angle thereto, whereby the foreign particles suspended in said gas are thrown to the outer edge by centrifugal action and are entrained in the high velocity stream. The devices are so constructed that there is no substantial mixing of the two gas streams, and the gas being cleaned is delivered at a higher pressure than that at which it is admitted to the devices.

In the drawing:

Figure 1 is a side elevation of an air cleaner embodying the invention;

Figure 2 is a section taken on the line 2—2 of Figure 1; and,

Figure 3 is a diagrammatic sketch illustrat-

ing the principle upon which the cleaner functions.

As shown in the drawing, the device is embodied in a unitary casing constructed in two sections to facilitate manufacture. An exhaust gas inlet 1 is adapted to communicate with an exhaust manifold of an engine, not shown. An air inlet 2 communicates with a source of air. The inlet 1 communicates with an exhaust gas supply conduit 3 in the casing. The air inlet 2 communicates with an air supply conduit 4 in the upper half of the casing. An exhaust outlet coupling 5 communicates with an exhaust discharge conduit 6 in the lower half of the casing. An air outlet coupling 7 communicates with an air discharge conduit 8 in the upper half of the casing.

The conduits 3, 4, 6 and 8 in the casing lie substantially parallel. The conduits 3 and 4 are circular in cross section and the discharge conduits 6 and 8 have a particular cross section for purposes to be hereinafter defined. A flat, thin passage 9 is formed between the exhaust supply conduit 3 and the discharge conduit 6 by machining the intermediate section of the faces of the two casing sections. The passage 10 adjacent the discharge conduit 6, as best shown in Figure 3, is considerably larger in the dimension at right angles to the flow path of the air therethrough, as indicated by the arrows, than the portion 9 of said passage adjacent the supply conduit 3. Intermediate the ends of said passage a depressed section 11 is milled into the lower half of the casing. The upper half of the casing is also cut away to form a passage 12 communicating in a stream-like manner with the air discharge conduit 8. The depressed section 11 and the cut away portion of the upper half of the casing thereabove form a chamber larger in cross sectional area than the passages 9 and 10. A thin passage 13 extending the length of the air supply conduit 4 communicates with said conduit and with the passage 9 at the end of its narrow portion and adjacent the enlarged portion formed by the depression 11 and the throat 12.

In the operation of this device exhaust 100

gas under pressure is delivered to the supply conduit 3. A flat stream of exhaust gas at comparatively high velocity is discharged through the passage 9. Upon being released from side wall pressure, due to the depression 11 and the throat 12, the stream expands and the discharge assumes a high velocity with a slight uniform expansion. The relative proportion of the passages is so designed that when operating at the pressures for which the device is designed, the gas stream issuing to the passage 9 expands during the interval over the depression 11 so that it substantially fills the passage 10 without having undue friction on the walls of the passage 10 and without leaving any substantial space between the stream and the walls. Air to be cleaned is supplied through the conduit 4 at substantially atmospheric pressure. The stream of gas issuing through the passage 9 has an injector action, which creates a depression through the passage 13, causing the air to flow therethrough. The stream of air issuing through the passage 13 impinges against the stream of exhaust gas issuing through the passage 9. Due to the sharp turn of the air at this point, the heavier foreign particles carried in suspension are thrown to the outer edge by centrifugal force and are entrained in the exhaust stream. Said particles are carried out with the exhaust gas through the conduit 6. A pressure is built up in the throat 12 by the surface friction of the air stream with the exhaust stream, and air is thereby delivered to the conduit 8 at a higher pressure than that at which it is admitted through the conduit 4. This in effect amounts to super-charging the air, and, instead of the depression created by the conventional air cleaners, this cleaner increases the pressure on the air, or super-charges it, resulting in an increased maximum horsepower for the engine to which the air is being supplied.

Although my invention has been illustrated and described as embodied in a device particularly adapted as an air cleaner for internal combustion engines, the device may be utilized wherever found desirable for moving, cleaning, or compressing one gas by the action of another gas available at a high pressure.

What is claimed is:

1. A device for cleaning a gas which comprises means for producing a flat stream of a cleaning gas at comparatively high velocity, means for directing a flat stream of the gas to be cleaned into contact with said stream, and means for subsequently separating the paths of travel of said gases thereby preventing substantial mixing.
2. An air cleaner for internal combustion engines which comprises means for producing a flat stream of exhaust gas at high velocity, means for directing a flat stream of

air into contact with said stream, and positive means to subsequently maintain the air and exhaust gas streams in separate paths.

3. A device for cleaning a gas which comprises means for producing a flat stream of a cleaning gas at comparatively high velocity, means for directing a flat stream of the gas to be cleaned into contact with said stream at an angle thereto, and means for separating the flow paths of the gases whereby substantial mixing is prevented. 70 75

4. A super-charger air cleaner for internal combustion engines comprising a chamber means for directing exhaust therefrom through said chamber, means for introducing air to be cleaned to said chamber, and means for delivering air from said chamber, said exhaust directing means being adapted to draw air into the chamber and to deliver it therefrom at an increased pressure. 80 85

5. In a super-charger air cleaner for internal combustion engines, a chamber means to direct exhaust gas through said chamber in an expanding stream at a comparatively high velocity, thereby creating a depression area and an area of increased pressure in said chamber, air inlet means to said chamber communicating with the area of depression, and air outlet means communicating with the area of increased pressure. 90 95

6. A device for cleaning and propelling one stream of gaseous fluid by direct contact with another stream of gaseous fluid without substantial mixing thereof, comprising a chamber, inlet means for delivering gas at 100 high velocity to the chamber through a wall thereof, outlet means from said chamber for the gas at high velocity of a cross sectional area greater than the inlet and positioned in a wall directly opposite the inlet, said chamber being so proportioned as to surround the high velocity gas stream in spaced relation thereto, means for delivering a low pressure gas to the chamber at the inlet end of the high velocity gas stream, and outlet means 105 for said gas adjacent the outlet end of the high pressure gas stream. 110 115

In testimony whereof I affix my signature.
ROBERT E. LYFORD.
